MOUNT FOR FOLDING DOORS

Charles S. Winn, 720 South 850 East,
Bountiful, Utah 84010

Filed Nov. 22, 1967, Ser. No. 9,502

Term of patent 14 years

Int. Cl. D8—03

U.S. Cl. D54—1

FIG. 1

FIG. 2

FIG. 3

FIG. 1 is a perspective view of a mount for folding doors, showing my new design;

FIG. 2, a side elevation view of the side that is hidden in FIG. 1; and

FIG. 3, a bottom plan view.

I claim:

The ornamental design for a mount for folding doors substantially as shown and described.
